UNITED STATES PATENT OFFICE.

CHARLES DAUCHE AND PATRICE DENIAUD, OF LA VILLE EN BOIS, FRANCE.

MACHINE FOR MANUFACTURING METAL BOXES.

SPECIFICATION forming part of Letters Patent No. 281,980, dated July 24, 1883.

Application filed September 21, 1882. (No model.) Patented in France December 17, 1881, No. 146,381, and in England August 12, 1882, No. 3,850.

To all whom it may concern:

Be it known that we, CHARLES DAUCHE and PATRICE DENIAUD, citizens of the Republic of France, residing at La Ville en Bois, in France, have invented Improvements in Machines for Manufacturing Metal Boxes, (for which we have obtained a patent in France, No. 146,381, dated December 17, 1881, and a patent in Great Britain, No. 3,850, dated August 12, 1882,) of which the following is a specification.

This invention has for its object mechanically to produce in metal boxes of all kinds a rapid and practicable joint. For producing such a joint a lever-press is used, and forms the joint in the following manner:

In the accompanying drawings, Figures 1, 2, 3, and 4 represent the joint in various phases of construction. Fig. 5 is a plan of the matrix. Fig. 6 is an elevation of the machine, partly in section. Fig. 7 is a plan of Fig. 6.

First the rim of the open metal box is pressed up by means of what is known as a "spinning-disk," whose outline is not sharp, but rounded, so as to avoid cracks in the edge, which is thus shaped somewhat as shown at T, Fig. 1. Then the lid, which is produced in the usual manner, as represented in Fig. 2, is placed on the open metal box, (an india-rubber ring having first been placed into the channel or groove B.) The whole, being then as represented in Fig. 3, is placed into a matrix consisting of the two parts M M', Figs. 5 and 6. These two parts are connected at one side by the hinge r, while on the other side the connection is made by the spring-hook o and the

holdfast p. Over the matrix there is the stamp fixed on the beam, and consisting, first, of two semicircular rings A A', Figs. 6 and 7, which, by means of the arms R R and the ring R', are connected with the vertical bar of the die P; second, of the interior stamp, P.

The beam S is fitted with some mechanical device that will enable the workman to operate it by foot. When the beam descends the two semicircular rings A and A' slide along the inner surface of the guide V till they arrive at the recessed part V', and there they move apart by reason of the pressure of the arms R R, and then afford free passage to the stamp P. As the inside edges of the semicircular rings are beveled off at an angle of about forty-five degrees, they give an oblique incline to the upper edge of the box, while the inner stamp, P, completes the horizontal folding, as represented in Fig. 4. The rubber ring placed into the channel B makes the joint hermetical.

What we claim, and desire to protect by United States Letters Patent, is—

1. The combination of the matrix M, divided hoop A, and stamp P, substantially as and for the purposes set forth.
2. The arms R R and collar R', as an automatically-adjustable attachment for the divided hoop A, substantially as and for the purposes set forth.

DAUCHE.
P. DENIAUD.
